UNITED STATES PATENT OFFICE

GEBHARD JAEGER AND JOSEPH EGGERT, OF COLUMBUS, OHIO, ASSIGNEES TO THE
JAEGER MACHINE COMPANY, OF COLUMBUS, OHIO, A CORPORATION OF OHIO

WATER TANK FOR CONCRETE MIXERS

Application filed April 18, 1931. Serial No. 531,022.

This invention relates more particularly to and has for its principal object the regulating of the quantity of water to be supplied to the dry materials of concrete in a mixing or conveying vessel. In carrying out the invention we employ a closed water tank in which a siphon is installed, said siphon being operable by means external to the tank and said tank being provided with a conductor discharging into the mixing drum and a tank filling opening provided with a closure, the removal of which is controlled by the position of the siphon so that additional water cannot be supplied to the tank while the siphon is in discharging position. Other objects will appear from the disclosure herein.

The invention is embodied in the example herein shown and described, the features of novelty being finally claimed.

In the accompanying drawing—

Figure 1 is a side view of a truck concrete mixer provided with means according to the invention.

Fig. 2 is a longitudinal sectional view of the tank on the line II—II Fig. 1, with some parts in full.

Fig. 3 is a cross section on the line III—III Fig. 2.

Fig. 4 is a section on the line IV—IV Fig. 2.

The mixing and transporting drum is mounted on an ordinary motor driven chassis having an engine within the usual hood 10, a driver's cab 11, a truck bed 12 supported by wheels 13, the rear pair of which is driven through a change speed gearing, not shown, but as usual.

The power for driving the shaft 34 may be derived from the vehicle propelling engine but in the instance shown there is secured to the truck bed an engine 37 distinct from that of the vehicle propelling engine, said engine 37 being preferably of the petrol type for said purpose.

The dry materials in the mixing vessel are supplied with water from a tank 50 connected with the hollow shaft 20 extending into the mixing vessel, said pipe 20 having connected with it a pipe 51 that extends upwardly into the tank about midway thereof

where it is provided with a swinging intake siphon 52. Said swinging siphon or intake 52 is provided with a manually operated shaft 53 having an external crank arm 53^a by means of which said intake can be swung to submerge its intake end into the body of water in the tank to withdraw from the tank for the mixing drum the quantity specified for mixture with the dry components of the concrete. The end of the tank adjacent the crank arm 53^a is provided with a graduated segment 54 for indicating the quantity of water that shall be withdrawn from the tank when the crank arm is moved to a particular mark on said segment.

The upper part of the tank in the path of the movement of the mouth of the siphon is provided with a flexible shield 55 to close the mouth of the siphon to prevent premature escape of water into the mixing drum as when traveling over a rough road to the place of a job. The only means provided for supplying the tank with water is through an opening in the top thereof, said opening being closed with a removable threaded plug 56 provided at its lower end with two lugs 57 projecting downward. Said plug incidently can be made with an axial opening to the atmosphere, said opening provided at the external end with an adjustable threaded valve 58 in a spring 59, said valve serving as a "poppet" to release excess pressure in the water tank, as herein-after referred to.

Fixed transversely on the shaft 53 within the tank is a semi-circular or sector-like plate 60 positioned in respect to the siphon 50 and lugs 57 so that when the siphon is swung to submerge its intake end and therefore discharge water from the tank, the rim of the plate stands between the two lugs and therefore prevents the turning of the threaded plug 56. This precludes the resupplying of water to the tank while the predetermined quantity or quantities of water are being withdrawn from the tank.

Any suitable stop lock at the proper point on the segment 54 can be provided to limit the degree movement of the crank arm 53 to permit only the withdrawal of the authorized quantity of water. Such a stop can consist of

any ordinary padlock 63 having its bolt inserted through one of a series of holes of the scale 54.

Pressure to force the water out of the tank 5 can be supplied by the exhaust of the engine 37 through a pipe 37^a connected with the top of the tank, and the poppet valve 58, heretofore referred to, limits such pressure according to the predetermined strength of the 10 spring 59 provided for acting on said valve.

Two baffle plates at 62 are provided to reduce turbulence of water in the tank when the mixer is being transported or otherwise, said plates having perforations along their upper 15 margins to permit the rapid distribution of the gas pressure over the surface of the water.

The water tank is shown as provided with an ordinary "gage" 61 to visibly indicate depth or quantity of water in the tank.

20 A branch conductor 64 connects the bottom of the tank with the discharge 51, said conductor being provided with a control valve 65 for supplying water to the mixing drum to flush the drum of concrete residue after the 25 mixing work is done and while such residue is soft. To preclude the unauthorized use of such conductor 64 said control valve 65 is locked or sealed in any suitable manner.

The forms of the parts can be changed 30 without departing from the gist of the invention as claimed.

What we claim is:

1. Means for supplying water to a concrete mixing or conveying vessel, said means including a water tank, a conductor leading 35 therefrom, a siphoning device operable externally of the tank for leading water to said conductor, said tank having a water charging opening and a closure therefor, and means 40 controlled by the position of the siphon for engaging said closure to prevent the removal of the latter.

2. Means for supplying water to a concrete mixing or conveying vessel, said means including a water tank, a conductor leading 45 therefrom, a siphoning device operable externally of the tank for leading water to said conductor, said tank having a water charging opening and a closure therefor, and 50 means controlled with the operation of the siphon to engage said closure to prevent the charging of said tank with water.

3. Means for supplying water to a concrete mixing or conveying vessel, said means including a water tank, a conductor leading 55 therefrom, a swinging siphoning device operable externally of the tank for leading water to said conductor, said tank having a water supplying opening and a closure therefor, and means carried with the swinging siphon to interfere with the removal of the closure when the siphon is swung to a water discharging position.

4. In means for supplying water to a concrete mixing or conveying vessel, said means

including a water tank, a conductor leading therefrom, a swinging siphoning device for leading water to said conductor, said tank having a water supplying opening and a rotating closure therefor provided with a lug, and a sector-like plate carried with the swinging siphon to stand adjacent said lug when the siphon is swung to discharging position to prevent the rotation of said closure.

5. In means for supplying water to a concrete mixing or conveying vessel, said means including a water tank, a conductor leading therefrom, a swinging siphoning device for leading water to said conductor, and a closure in said tank for the mouth of said siphoning device when the latter is in non-discharging position.

6. In means for supplying water to a concrete mixing or conveying vessel, said means including a water tank, a conductor leading therefrom, a swinging siphoning device for leading water to said conductor, and a flexible closure in said tank for the mouth of said siphoning device when the latter is in non-discharging position.

7. Means for supplying water to a concrete mixing or conveying vessel including a water tank, a conductor leading therefrom, a siphoning device having a depressible discharge for leading water from the tank into 95 said conductor, said tank provided with an opening for charging said tank with water, a movable closure for said tank charging opening, and means operable concurrently with the depression of the siphoning device 100 to lock said closure in closing position.

8. Means for supplying water to a concrete mixing or conveying vessel including a water tank, a conductor leading therefrom, a siphoning device having a depressible discharge for leading water from the tank into 105 said conductor, said tank provided with an opening for charging said tank with water, a movable closure for said tank-charging opening, and means operable upon the depression of said siphoning device for preventing opening movement of said closure while the discharge of the siphoning device is in a depressed position.

9. Means for supplying water to a concrete mixing or conveying vessel including a water tank, a conductor leading therefrom, a siphoning device having a depressible discharge for leading water from the tank into 115 said conductor, said tank provided with an opening for charging said tank with water, a rotatable closure to engage said tank to close said opening, and means operable upon the depression of the siphoning device to engage said closure to prevent rotation thereof 120 to open said tank-charging opening.
